CLAYTON L. KENYON, OF MINNEAPOLIS, MINNESOTA, ASSIGNOR TO KENYON MANUFACTURING COMPANY, OF MINNEAPOLIS, MINNESOTA, A CORPORATION OF DELAWARE

PUMP JACK

Application filed October 5, 1925. Serial No. 60,466.

My invention relates to pump jacks and has for its object to provide a jack which may be rigidly secured to a pump proper so as to cause the same to effectively function without lost motion.

Another object of the invention resides in providing a circular casing in which the operating mechanism of the invention is positioned so as to completely cover the same from the rain and weather and to provide an oil reservoir so that the mechanism may at all times operate in a bath of oil.

Another object resides in providing a T-shaped lever, the stem of which projects downwardly into the casing and is oscillated by means of a crank pin mounted on a gear, while the cross bar thereof extends outwardly beyond the casing and is connected at one end to the pump rod and at its other end to an equalizing coil spring.

Another object of the invention resides in forming said casing with a sector shaped opening to permit of inserting the main gear into the same and to provide the oil reservoir at the bottom of the casing.

A still further object resides in forming said casing at the upper portion thereof with an opening through which the stem of said T-lever may be projected, and to offset the bar of said T from said stem and to provide a cover for closing said opening.

Another object of the invention resides in providing a coil spring attached to the cross arm of said T lever for the purpose of counter balancing the action of the pump upon its return stroke.

A still further feature resides in providing oil pockets in the cross head block to cushion the same along the guide way so as to reduce the wear of said cross head and guideway.

Other objects of the invention reside in the detailed construction thereof as brought out in the following description, claims and drawings.

In the drawings illustrating my invention in one form:

Fig. 1 is a side elevational view of the device attached to the base of a pump with the cover of the casing removed.

Fig. 2 is a plan view of the structure shown in Fig. 1.

Fig. 3 is a sectional view taken on line 3—3 of Fig. 1.

Fig. 4 is an isometric view of the cross head 55 of the invention.

My invention is adapted to be used in connection with pumps such as employed for wells and cisterns and is arranged to operate the pump rod thereof in a manner well known 60 in the art.

In the drawings I have illustrated a portion of the standard 10 of an ordinary pump A which is supported upon the usual base 11. Such pumps being well known in the art I 65 have not thought it necessary to illustrate the same in greater detail.

The invention proper consists of a casing B, which is circular in formation and has formed on it legs 12 and 13 by means of which 70 the same may be secured to a suitable support.

The leg 12 is formed with an upstanding flange 14, while the casing proper has a boss 15 issuing outwardly from it above said flange. To this flange and boss are bolted by means of bolts 16 and 17, a bracket 18, which is formed with a V shaped neck 19, best illustrated in Fig. 2. This neck is adapted to lie adjacent the standard 10 of the pump A and 80 a clamp member 20 of similar shape is positioned on the opposite side thereof and attached to it by means of bolts 21. When the casing B is secured to the platform on which the pump A rests and the bracket 18 and 85 clamp 20 rigidly bolted together to embrace the pump standard 10 it can readily be seen that the structure is securely and rigidly held in place.

At the upper end of the casing B is provided a transverse shaft 22, which is firmly secured in two bosses 23 and 24, formed in the casing B. This casing is arranged with a raised portion 25 near the boss 24 and a depressed portion 26 adjacent the boss 23, which 90 depressed portion is continuous with the remaining circular part of the casing. Upon the shaft 22 is journaled a T-shaped lever indicated in its entirety at C, which 95 comprises a horizontally positioned lever por-

tion 27 issuing from it at one end and a rearwardly extending arm 28. The said T-shaped lever further includes a depending guide arm 29 which, together with the lever 27 and arm 28, are integrally connected to a boss 30 journalled upon a shaft 22 between the bosses 23 and 24. It will be noted that the lever 27 and the arm 28 are in alignment and extend outwardly beyond the casing along the depressed portion 26 thereof, and that the depending guide arm 29 extends through the opening in the raised portion 25 of the casing and into the interior thereof.

Oscillating movement is imparted to the depending guide arm 29 in a manner to be presently described, which causes the lever 27 to be raised and lowered. This lever is preferably formed with a yoke 34 which is connected to the usual bars 32 of the pump proper, which in turn are pivoted to the pump rod 33 and cause the pump to function in the ordinary manner.

Upon the end of the arm 28 is formed a boss 35 through which loosely passes a pin 36, held in place by means of a nut 37 and a locknut 38. This pin has secured to it a coil spring 39, which in turn is secured at its other end to a lug 40, cast integral with the leg 13 and the body of the casing proper.

As the pump operates the spring 39 is caused to be elongated during the return stroke of the pump which assists in raising the pump rod during the effective stroke, thereby causing the device to operate more smoothly and produce the results desired.

Within the casing B is positioned a spur gear 41 journalled upon a stub shaft 42 which is mounted in a boss 43 formed in the center of the circular portion of the casing B.

This casing is of such a size as to conveniently enclose the gear 41 which travels but a short distance from the bottom of the same. At the upper end of the casing B are formed two bearings 44 and 45 in which is journalled a shaft 46 extending through the device on one side and which carries a pinion 47 meshing with the spur gear 41. This pinion, as will be noted, is arranged within an enlarged portion 48 of the casing B so that the same and the gear 41 are completely enclosed within the casing.

The gear 41 is provided with a number of bosses 49, 50 and 51 which are positioned between the spokes of said gear and are arranged at different distances from the center of the shaft 42. A pin 52 formed with a shoulder 53 is adapted to be inserted into the bores 54 of any of the bosses 49, 50 or 51 so as to protrude outwardly therefrom. This pin may be secured in place upon said bosses by means of a nut 55 screwable upon the end thereof. The pin 52 is journalled in its protruding position in a cross head block 56 shown in detail in Fig. 4. This block is

bored at 57 to receive the pin 52 and slides longitudinally along a rectangular guideway 58 formed along the guide arm 29. It can readily be comprehended that as the gear 41 is rotated the arm 29 and consequently the lever 27 are caused to be oscillated by means of the cross head 56 and the pin 52. It will further be noted that the pin 52 being closer to the shaft 22 during the upper half of the rotation of gear 41 that the movement of the lever 27 is much more rapid than when the said pin is more remote from the shaft 22 during the lower half of the rotation of gear 41. This principle is utilized in causing the device to operate smoothly by having the effective stroke of the pump occur while the pin 52 is remote from the shaft 22 and the return stroke occur when the pin 52 is in close proximity to the shaft 22.

For closing the opening at the raised portion 25 of casing B I provide a detachable closure 59 which is adapted to be secured to said casing by means of two cap screws 60.

This closure is arranged with a wall 61 which fits around the boss 24 and with a similar wall 62 fitting around the boss 30 of the lever C. A similar wall 63 formed on the casing proper fits along the under side of the boss 30 and meets with a wall 62 to form a water-tight enclosure for the interior mechanism of the jack. It will be noted that the depending guide arm 29 and the lever 27 and arm 28 are offset in relation to one another so as to permit the walls 62 and 63 to fall between the same and to close the interior of the casing with a tight joint.

In assembling the invention the gear 41 is first slid into the casing B through a segmental shaped opening 64 which is arranged in the upper portion of said casing leaving a wall 65 at the lower portion thereof cast integral with the remainder of the casing, to form an oil reservoir indicated at 66 in Fig. 3. After the gear has been placed within the casing the shaft 42 is passed through the boss 43 and through a bushing 71 in said gear where the same is held in place by a cotter pin 72 and a set screw 73. The T-shaped lever C is next assembled by dropping the guide arm 29 through the opening at the raised portion 25 of casing B and sliding the same over the cross head 56 which is mounted upon pin 52. After this has been properly positioned the shaft 22 is passed through the bosses 23 and 24 and through bushings 74 and 75 in the boss 30, said shaft being held in place by set screws 76 and 77. The opening may be closed by a plate 67 secured to said casing by means of screws 168. The oil may be inserted into the device by removing the cap 59 and filling the same through the opening in the raised portion 25 of said casing. As the device is operated through a pulley 68 secured to the protruding end of the shaft 46 or any other suitable means, the oil within the reservoir 66 is

splashed about upon the interior mechanism of the jack causing the same to be at all times properly lubricated. A drain 69 placed at the bottom of the casing B permits of draining the oil whenever it is desired.

- 5 To reduce the wear on the cross head block 56 I drill a number of holes 70 along the sides of the same where they engage the walls of the guide 58. As the device functions these holes which serve as pockets become filled with oil.
- 10 As the gear 41 rotates the block 56 is thrown from side to side of the guide 58 causing the oil retained within the pockets 70 to be squeezed out of the same and between the contacting surfaces, thereby cushioning the shock imparted to said block for every stroke of the pump and consequently reducing the wear of the guide and said cross head block.

The invention is particularly advantageous in that the jack may be rigidly secured to the pump proper so that no lost motion occurs due to loose fastening to the supporting platform. In addition the entire construction is completely enclosed in a weather proof casing so that the interior mechanism of the same is preserved. At the same time an oil reservoir is formed which will carry a sufficient quantity of oil to keep the device properly lubricated at all times. The device may be readily assembled without considerable difficulty and the casing proper may be constructed of a single casting so as to reduce the cost of the same and to provide an integrally formed oil reservoir. The cushioning spring and the arrangement of the mechanism for oscillating the lever arm cause the jack to function in an efficient manner with practically the same stress executed upon the return stroke as upon the effective stroke thereby causing the operating motor and jack to run smoothly and quietly.

Having described my invention in the form which I consider to represent the best embodiment thereof I desire to have it understood that the invention may be constructed in different ways and put to uses other than those described within the scope of the following claims.

Claims:

- 60 1. A pump jack comprising a circular casing, a shaft mounted in the upper portion thereof, said casing having a raised portion formed with an opening therein and a depressed portion adjacent said raised portion, a T-shaped lever journalled on said shaft having a cross bar portion arranged along the depressed portion of said casing outwardly therefrom and a stem portion protruding through said raised portion and into the interior of said casing and a cap for closing the opening in said raised portion of the casing.

65 2. A pump jack comprising a casing, a shaft mounted in the upper portion of said casing, a lever, journalled upon said shaft

positioned wholly without said casing, a depending guide arm secured to said lever in offset relation thereto projecting wholly within said casing, means for enclosing the upper portion of said casing and means for actuating said guide arm to oscillate said lever.

3. In combination with a pump jack having a guide bar, a cross head block slidable along said guide bar, said cross head block being formed with transverse pockets and means for freely discharging oil upon said cross head block.

4. A pump jack comprising a casing having a raised portion formed with an opening therein and a depressed portion adjacent said raised portion, a pair of bosses formed upon said casing adjacent said raised and depressed portions, a shaft mounted between said bosses, a boss positioned between said bosses and journalled upon said shaft, said last named boss carrying a depending guide arm protruding into the interior of the casing, a lever formed on said boss in offset relation to said guide arm and extending along the depressed portion of said casing on the exterior of the device, said raised portion of said casing forming a wall fitted around said last named boss between said depending guide arm and lever, a cap for closing the opening in said raised portion having a wall meeting the wall of said raised portion, said cap surrounding the upper portion of said last named boss and forming a tight closure for said casing.

5. A pump jack comprising a substantially cylindrical casing having a raised portion centrally positioned relative thereto at the upper portion thereof, a gear concentrically positioned within said casing, a shaft mounted in the raised portion of said casing, a lever pivoted on said shaft, said lever having two horizontal arms extending outwardly therefrom in opposite directions and a vertical arm depending within said casing, means operated by said gear for rocking said vertical arm, a counter balance connected to one of said horizontal arms, said other horizontal arm being arranged for connection to a pump rod.

6. A pump jack comprising a casing, having a wall, a lever pivoted thereto, said lever having a cylindrical portion concentric with its axis passing through said wall at right angles thereto, said lever having an arm connected with said cylindrical portion positioned exteriorly of said casing on one side of said wall, and being adapted to be connected to a pump rod, said lever having another arm positioned interiorly relative to said casing on the other side of said wall and connected to said cylindrical portion, and means for oscillating said second named arm.

7. A pump jack comprising a cylindrical casing, said casing having a portion extending upwardly above the periphery of the

major portion thereof to one side of said casing, a lever pivoted to said casing, said lever having a cylindrical portion concentric with its axis extending through said raised portion of said casing, said lever having an arm 5 positioned above the cylindrical portion of said casing adjacent said raised portion on the exterior thereof adapted to be connected to a pump rod and an arm positioned within said raised portion and interiorly in said casing, and means within said casing for rocking said arm.

8. A pump jack comprising a casing, a T shaped lever pivoted to said casing substantially centrally thereof near its upper 15 portion, said lever having an arm extending to either side of said case without the same and a stem depending within the case, one of said arms being arranged for connection to a pump rod, a counter-balance connected to 20 the other arm, and means within said casing for engaging said stem for operating said lever.

In testimony whereof I affix my signature.
